UNITED STATES PATENT OFFICE.

JAMES H. RAND, OF NORTH TONAWANDA, NEW YORK.

CARD RECORD AND INDEX.

SPECIFICATION forming part of Letters Patent No. 664,501, dated December 25, 1900.

Application filed July 14, 1900. Serial No. 23,667. (No model.)

To all whom it may concern:

Be it known that I, JAMES H. RAND, a citizen of the United States, residing at North Tonawanda, in the county of Niagara and State 5 of New York, have invented new and useful Improvements in Card Records and Indexes, of which the following is a specification.

This invention relates to a card record and index designed to be used, for instance, in 10 banks and mercantile establishments in place of the ordinary account and record books; and it has for its object to provide a compact and convenient device of this kind which 15 simplifies the keeping of accounts and records and permits a ready reference to the same.

In the accompanying drawings, consisting of two sheets, Figure 1 is a top plan view of my improved device. Fig. 2 is a fragmentary vertical longitudinal section thereof, 20 showing the record or account cards in place in the pockets. Fig. 3 is a similar view with the cards removed. Fig. 4 is a vertical cross-section of the device in line 44, Fig. 1. Fig. 25 5 is a fragmentary vertical section in line 55, Fig. 3.

Like letters of reference refer to like parts in the several figures.

A is a rectangular case or drawer which is 30 open at its top and divided by transverse partitions B into a number of upright pockets or compartments C. These pockets may extend from side to side of the case or the case 35 may be divided by a central longitudinal partition D into two sets of pockets, as shown in Figs. 1 and 4. When two sets of pockets are employed, the partitions B preferably extend continuously from side to side of the case, and each partition is provided centrally with 40 an upright notch b, which extends upwardly from the lower edge thereof and receives the longitudinal partition D.

The pockets C are adapted to receive a number of removable record or account cards E, 45 upon each of which a separate or individual account or other record may be kept, the cards being suitably ruled for this purpose, as shown in Fig. 4. Each card is provided at its upper edge with a projecting tab e for 50 withdrawing it from its pocket.

At the upper edge of each transverse partition B is arranged a transverse index flap

or leaf F, which is preferably hinged or flexibly connected with said partition, so that the flap can be turned in either direction to a 55 horizontal or nearly-horizontal position, as shown in Figs. 2 and 3. Each of these index-flaps is provided with name-spaces, which are adapted to receive the names or designations of the cards placed in the corresponding 60 pocket or pockets and which are arranged at right angles to the cards. These names are preferably written on removable slips f, which are inserted in suitable open-faced 65 holders f', secured to the face of the index-flap, one below another, although the names may be written directly upon the flap, if desired. The tabs of the cards E seated in the same pocket are arranged out of line with one another, and each card has its tab located directly opposite or in line with that 70 name of the index-flap which corresponds to the card. By this arrangement when it is desired to examine a certain card or make an entry thereon it is only necessary to refer to 75 the name of that card on the index-flap and then seize the tab in line with said name and withdraw the card. For example, should it be desired to make an entry on J. Ames's account the accountant finds that name on the 80 index-flap and withdraws the proper card from the pocket by seizing the tab directly opposite said name. This can be done more quickly than an account can be found in an ordinary index-record book or ledger, where 85 it is necessary to refer first to the index for the page-number of the account and then turn to the proper page in the book. In replacing a withdrawn card it is not necessary to put the same in any particular place in its 90 pocket; but it may be inserted at random anywhere in the pocket, inasmuch as its tab will always stand in line with the corresponding name on the index-flap, whether 95 the card be near or remote from the flap.

In order to center the cards lengthwise in their pockets and insure an accurate register of their tabs with the corresponding names of the index-flaps, the lower portions of the pockets are constructed to fit the cards snugly 100 when fully inserted and their upper portions are flared, or, in other words, the upper portions of their end walls are constructed to converge downwardly, as shown in Fig. 4. By

this construction the cards can be easily inserted in their pockets, and they are at the same time properly centered therein in depressing them to the bottom of the pocket. 5 The downwardly-converging ends of the pockets are preferably formed by upright guide or filling strips $g\ g'$, having vertical lower portions which are separated from the adjacent side walls, and the longitudinal partition D 10 of the case A by blocks g^2 , secured to the backs of the strip, while their upper portions are inclined from the upper edge of the case toward the upright lower portions of the strips. The filling - strips g , located at the 15 outer ends of the pockets, are provided at their upper ends with hooks g^3 , which engage over the upper edges of the side walls of the case, while the opposing filling-strips g' , located at the inner ends of the two sets of 20 pockets, are preferably formed of a single piece of metal, which is doubled over the upper edge of the longitudinal partition D. These centering-strips and the transverse partitions B are arranged loosely in the case, so 25 that they can be shifted or adjusted lengthwise of the case for making the card-pockets wider or narrower, as may be desired. The last or rearmost partition is held in its proper upright position by an abutment - plate H, 30 having a suitable brace h. The centering-strips $g\ g'$ also serve to properly separate the loose partitions B.

A greater or less number of card-pockets C and corresponding index-flaps F may be employed, according to the requirements of the 35 particular business in which the device is used. When two or more card-pockets and index-flaps are employed, as shown in the drawings, the flaps overlap each other like the leaves of 40 an open book, and they can be readily turned in one direction or the other for exposing the flap which bears the name or designation to which it is desired to refer. Each flap bears the names belonging to a section of the 45 alphabet, the first flap bearing names which begin, say, with "A" and "B," the second flap those beginning with "C" and "D," and so on, in an obvious manner.

The device not only saves considerable time 50 in referring to the accounts or records, but it is also very compact, permitting a large number of accounts or records to be kept in a comparatively small compass. The case may be constructed in the form of a sliding drawer 55 which is inclosed by a suitable cabinet, or it may be seated in an opening or recess in the top of a desk with the index-flaps flush with the top of the desk.

The device is especially desirable for savings-banks and other institutions or business 60 houses having a large number of small accounts, and it may also be used as a signature-index for banks.

When the record or account cards are filled

up, they are placed in a suitable file provided 65 for the purpose and new cards are substituted therefor in the card record and index.

I claim as my invention—

1. In a card record and index, the combination with a case having a pocket or compartment, of a folding index flap or leaf arranged at the upper end of said pocket and attached to one of the walls thereof, and record or account cards arranged in said pocket and provided at their upper edges with 75 tabs which correspond to the names or designations of said index-flap, substantially as set forth.

2. In a card record and index, the combination with a case having two or more upright card-pockets, of horizontal index flaps or leaves arranged at the upper ends of said pockets and flexibly attached to one of the side walls thereof, and record or account cards arranged in said pockets and provided at 80 their upper edges with tabs which correspond to the names or designations of said index-flaps, substantially as set forth.

3. In a card record or index, the combination with a case having a pocket or compartment, of internal upright centering-strips located at the ends of said pocket and each having an inclined upper portion and a vertical lower portion arranged inwardly beyond 90 said inclined portion, and record or account 95 cards seated in said pockets against said centering-strips, substantially as set forth.

4. In a card record and index, the combination with a case having a pocket or compartment, of internal upright centering-strips 100 located at the ends of said pocket and having their upper ends loosely engaged with the end walls of the pocket, and each having an upper inclined portion and a lower vertical portion arranged inwardly beyond said inclined portion and provided with a backing-block which bears against the end wall of the pocket, and record or account cards seated in said pocket against said centering-strips, 105 substantially as set forth.

5. In a card record and index, the combination with a case and a number of transverse partitions arranged adjustably therein and forming upright card-pockets, of index-flaps flexibly connected to the upper edges 115 of said partitions and adapted to overlap each other, and record or account cards arranged in said pockets, and each provided at its upper edge with a tab which is located in line with the corresponding name or designation 120 of the adjacent index-flap, substantially as set forth.

Witness my hand this 21st day of May, 1900.

JAMES H. RAND.
